UNITED STATES PATENT OFFICE.

EDGAR W. ANDERSON, OF MANITOWOC, WISCONSIN, ASSIGNOR TO INVINCIBLE METAL FURNITURE COMPANY, OF MANITOWOC, WISCONSIN, A CORPORATION OF WISCONSIN.

LOCK MECHANISM.

Application filed March 6, 1923. Serial No. 623,087.

To all whom it may concern:

Be it known that I, EDGAR W. ANDERSON, a citizen of the United States, and a resident of Manitowoc, in the county of Manitowoc and State of Wisconsin, have invented an Improved Lock Mechanism, of which the following is a specification.

This invention relates to locks and relates particularly to locks for the cell doors of safe-deposit boxes and the like, of the general type which forms the subject-matter of U. S. Letters Patent No. 1,436,925, dated November 28, 1922.

The object of the present invention is to provide improved, simplified and relatively inexpensive mechanism for actuating the auxiliary bolt or bolts positioned within the door to which the lock is applied, designed to safeguard the door from being pried open.

To effect this object, a lock mechanism embodying my invention and improvements comprises the various features, combination of features and details of construction hereinafter described and claimed.

In the accompanying drawings in which my invention is fully illustrated,

Figure 1 is a front view of a safe-deposit unit comprising two cells, one of said cells being shown complete and the door thereof being closed.

Figure 2 is a sectional plan view thereof, on the line 2—2 of Fig. 1.

Figure 3 is a sectional front view on the line 3—3 of Fig. 2.

Figure 4 is a detached rear view of a lock embodying my invention and improvements, showing the means for actuating the auxiliary bolts, positioned in the wall of the cell door; and

Figures 5 and 6 are detached views of parts of the mechanism for actuating said auxiliary bolts.

Referring now to the drawings, A designates as a whole, the casing of a safe-deposit unit, comprising top and bottom walls 1 and 2, side walls 3, and a rear wall, not shown. The interior of the unit A is divided by a partition or partitions 4 into cells 5, the front sides of which are closed by doors 6 pivoted at one edge to hinge pins 7. The doors 6 are adapted to be secured in closed position by locks 8 secured to the inner sides of said doors in proper

position, the bolts 9 of which are adapted 55 to engage a shoulder 10 formed in proper position on the partition 4.

As regards their usual features, and excepting as hereinafter particularly described and pointed out, a safe deposit unit of my invention may be of any desired or approved construction, and will readily be understood by persons familiar with the art from an examination of the drawings and without a description thereof in detail. 65

Also, each unit A may have any desired number of cells 5, the sizes of which may vary according to requirements.

In addition to the locking bolt 9, a lock mechanism embodying my invention comprises auxiliary bolts 11 and 12 which are slidably fitted, respectively, to holes 13 and 14 formed in the door 6, substantially parallel with the hinge pins 7 and which are respectively adapted to engage holes 15 and 75 16 formed in the top and bottom walls 1 and 2, respectively, of the unit A.

The casing of the lock 8 is secured to the inner side of the door by means of screws 17 and secured to the inner side thereof is 80 a bar 18, the inner ends of which are adapted to rest in contact with shoulders formed on the top and bottom walls of the unit A, the shoulder on the bottom wall being shown at 19, Fig. 2. Said bar 18 safeguards the 85 lock 8 from being driven inwardly into the cell 5 by stripping the threads of the screws 17, all as fully described in said U. S. Patent No. 1,436,925.

As shown, the main bolt 9 of the lock 8 90 is of the usual type adapted to be operated by means of separate keys, comprising a master key which remains in the possession of the vault attendant, adapted to engage a key slot formed in the barrel 20 of the lock 8, and a second key which is delivered to and remains in the possession of the proprietor of the box, adapted to engage a key slot formed in the key barrel 21, said key barrels 20 and 21 being rotatably mounted 95 in housings 22 and 23, respectively, which engage holes formed in the door 6, the ends thereof extending substantially flush with the outer side of said door.

As regards the mechanism for actuating 105 the main bolt 9 of the lock 8, said lock may be made of any usual or approved construction. Locks suitable for the purpose

may be purchased commercially and said operating mechanism need not, therefore, be described in detail.

The auxiliary bolts 11 and 12 form no part of the lock 8 proper but, as previously stated, are mounted in holes formed in the door 6 so as to be movable endwise therein and are adapted to be actuated by suitable connection with the operating mechanism of the main bolt 9 of the lock, in the following manner:— Mounted to turn on the housing 23 of the key barrel 21 is a ring 24 formed on which are lugs or projections 25 and 26 adapted to engage notches 27 and 28 formed in said auxiliary bolts, the door 6 being provided on its inner side with a recess 29 adapted to permit engagement of the lugs or projections 25 and 26 with the notches 27 and 28 and turning movement of the ring 24.

With the described construction, it is obvious that turning movement of the ring 24 with the lugs or projections 25 and 26 thereon, in engagement with the notches 27 and 28 in the auxiliary bolts 11 and 12, will operate to advance or retract said bolts as said ring is turned in one direction or the other. In the preferable construction shown, the ring 24 is operatively connected to the main bolt 9 of the lock 8, the relation being such that when said bolt 9 is advanced and retracted, turning movement will be imparted to the ring 24 in a direction to advance and retract the auxiliary bolts 11 and 12 coincident with advancement and retraction of the bolt 9.

As shown, the connection between the bolt 9 and the ring 24 consists of a link 30, one end of which is pivoted to a lug 31 on said ring and formed in the other end of which is a hole 32 which is adapted to engage a lug or projection 33 on the bolt 9, which extends through a slot 34 formed in the rear wall of the lock casing, said projection 33 and slot 34 being proportioned to permit contemplated movement of the main bolt 9 in operation.

In use, the ring 24 is designed to rest in contact with the rear side of the casing of the lock 8, the thickness of said ring and the length of the projections 25 and 26 being so proportioned that the overall dimension of said ring from the outer ends of the projections 25 and 26 to the remote side

of said ring will be substantially equal to 55 the distance between the bottom of the recess 29, and the rear wall of the lock 8, sufficient clearance being provided, however, to permit said ring to turn freely on the housing 23 of the key barrel 21, without 60 binding.

As shown, the pivoted end of the link 30 is confined between the rear wall of the casing of the lock 8 and the projection 31 on the ring 24, said ring and lug being cut 65 away, as shown at 35 to a depth slightly greater than the thickness of said link.

While I have herein shown two auxiliary locking bolts, I do not desire to limit myself thereto, as good results would be obtained with the use of a single bolt only. In other words, within the contemplation of my invention, a construction in which two auxiliary bolts or only a single bolt is used, are considered to be equivalents one 75 of the other.

I claim—

1. The combination of a door and locking mechanism therefor, comprising a main bolt and an auxiliary bolt or bolts, and 80 mechanism for actuating said bolts to advance and retract the same, the means for actuating said auxiliary bolt or bolts comprising a rotatable ring, projections thereon which engage a notch or notches formed 85 in said auxiliary bolt or bolts, and connection between said ring and the main bolt of the locking mechanism, substantially as described.

2. A door and locking mechanism therefor as specified in claim 1, in which the connection between said main bolt and the auxiliary bolt or bolts for actuating the latter, consists of a link, one end of which is pivoted to said ring and the opposite end of 95 which is connected to a lug or projection on the main bolt of the locking mechanism, substantially as described.

3. A door and locking mechanism therefor as specified in claim 1, in which the 100 rotatable ring for actuating the auxiliary bolt or bolts is mounted on the housing of a key barrel, substantially as described.

In witness that I claim the foregoing as my invention, I affix my signature this 13 105 day of February, A. D. 1923.

EDGAR W. ANDERSON.
